UNITED STATES PATENT OFFICE.

WILLIAM R. MARSHALL, OF HOLYOKE, MASSACHUSETTS, ASSIGNOR TO THE HOLYOKE COMPANY, INC., OF HOLYOKE, MASSACHUSETTS, A CORPORATION OF MASSACHUSETTS.

SPOOL CONSTRUCTION.

Application filed January 15, 1926. Serial No. 81,521.

This invention relates to improvements in spools particularly of the type adapted for holding or supporting a so-called bundle or coil of wire in such a manner that the wire 5 of the coil may be unwound therefrom.

It is common practice for wire manufacturers to market wires of various sizes and kinds in the coils or bundles above referred to, and in order for the user thereof to unwind the wire it is usually placed on a support of some sort or on spools.

Spools for receiving these bundles, with which I am familiar, usually comprise a central barrel having heads or flanges at either 15 end, one or both of which are removable to permit the barrel to be inserted in the coil. These offer disadvantages and are objectionable for the reason that the turns of the wire in the coil are liable, when under tension 20 in being pulled off the coil, to fall into the crevice between the removable head and barrel. Also when the head is being secured onto the barrel a turn or more of the wire is liable to be squeezed therebetween and 25 subsequently broken when under tension in unwinding.

According to one feature of my invention I provide a spool having a barrel and heads arranged to be separated intermediate the 30 adjacent faces of the heads whereby I eliminate the possibility of injuring the endmost turns of the coil. As a further feature of the invention the interfitting members of the spool are arranged so as to tend to cam the wire outwardly from the abutting parts 35 rather than clamp the same therebetween.

There are many changes that may be made in the form of the invention shown without departing from the scope thereof, the form 40 shown being merely a disclosure of the invention in the present preferred embodiment thereof.

In the drawings:—

Fig. 1 is a side elevational view of a spool 45 embodying the features of the invention;

Fig. 2 is a side elevational view of the parts in a disassembled relation; and

Fig. 3 is an isometric view at small scale 50 of a bundle or coil of wire.

Referring to the drawings in detail the spool comprises separable portions 1 and 2 each of which includes a barrel 3 and 3' 55 preferably integral with heads or flanges 4

and 4' respectively. The barrel 3 has its inner end shaped in the form of a tapering 60 cone and terminates in a shank 5 that is screw threaded on its outer end as shown.

The inner end of the barrel 3' is chamfered out to fit over the cone shaped end of the barrel 3 and receives the threaded end 5 65 of said barrel. A nut 6 is provided for screwing onto the barrel 3 and is adapted to clamp the parts together. A noncylindrical projection at the rear of the flange 4 is provided by the means of which this portion of 70 the spool may be embraced or held against turning by any suitable tool. Both barrel portions are provided with a central axial bore 7 for receiving an arbor or the like by the means of which the spool may be supported for an unwinding operation.

The proportions of the various parts may be as desired, or according to the particular coil that the spool may be used with. Slots such as 8 and 9 may be provided in the faces 75 of the heads and barrel as shown for receiving the projecting binding wires such as C' used to bind the bundle or coil of wire C for shipment. In operation a coil C of wire is slipped over the barrel 3' and the barrel 3 is inserted in the opening of the coil and opening of the barrel 3'. The nut 6 is screwed onto the thread of the barrel 3 and bearing on the face of the head 4' will draw the tapered interfitting portions of the barrels together. The noncylindrical projection of the flange 3 may be held in a vise or the like to prevent a rotative movement of the spool while the nut 6 is being drawn up 85 tightly to clamp the parts together. When 90 the coil is thus held on the spool, the binding wires may be removed and the spool slipped over a mandrel or the like and the wire unwound therefrom at any speed desired.

From the foregoing it will be noted that I have provided a spool of novel construction in which the barrel is separable intermediate the inner faces of the heads and that there are no abutting faces that are 100 likely to clamp and injure a turn of the coil therebetween.

What I claim is:

A spool comprising separable members 105 each having a barrel with a head or flange on its outer end, the inner end of one member

being provided with a tapering socket and the inner end of the other member being tapered to fit within said socket and a threaded shank extending forwardly of said 5 taper that projects through and beyond the head of the other member and a nut in engagement with said shank bearing against

said head for holding said taper and socket in interengagement so as to provide a spool having a barrel separable at a point midway ¹⁰ between its heads.

In testimony whereof I have affixed my signature.

WILLIAM R. MARSHALL.
